US0D1069690S

(12) **United States Design Patent** (10) **Patent No.:** **US D1,069,690 S**
(45) **Date of Patent:** **** Apr. 8, 2025**

(54) **BATTERY**

(71) Applicant: **Wu He**, Shenzhen (CN)

(72) Inventor: **Wu He**, Shenzhen (CN)

(**) Term: **15 Years**

(21) Appl. No.: **29/880,926**

(22) Filed: **Jul. 28, 2023**

(30) **Foreign Application Priority Data**

Jun. 12, 2023 (CN) 202330360753.3

(51) **LOC (15) Cl.** **13-02**

(52) **U.S. Cl.**

USPC **D13/103**

(58) **Field of Classification Search**

(57) **CLAIM**

The ornamental design for a battery, as shown and described.

DESCRIPTION

FIG. 1 is a front, top perspective view of a battery, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines in the figures illustrate portions of the
battery that form no part of the claimed design.

1 Claim, 8 Drawing Sheets
